Inventor

Charles E. White

By Clarence O'Brien

Attorney

UNITED STATES PATENT OFFICE

CHARLES E. WHITE, OF PENROSE, COLORADO

CONVERTIBLE LADDER

Application filed January 3, 1930. Serial No. 418,289.

This invention relates to an improved convertible ladder which is expressly, but not necessarily, adapted for use in fruit orchards, that is a ladder which is especially designed

6 in form and configuration to better fulfill the requirements of a structure of this class than ordinary or conventional ladders.

Otherwise stated, I have evolved and produced a simple and economical orchard ladder of the convertible type made up of properly associated companion sections susceptible of being arranged in longitudinal alignment for elevated work, or folded into an angular supporting relationship to function as

15 a relatively short step ladder.

In carrying the invention into practice, I have incorporated in this structure a number of distinguishable and novel features. First, I utilize an especially designed hinge

20 which is susceptible of distributing stress, assuring a sturdy joint, and permitting converting of the ladder sections.

Secondly, I embody in this hinge a novel latch for holding the leaves either in acute

25 angular relationship for step ladder construction, and in perfect longitudinal alignment for an extension ladder construction.

In addition, I provide a convertible ladder of this type which is characterized by an ap-

30 propriate balancing base including extension legs appropriately fastened to the lower or main ladder section, the construction and arrangement being such as to promote strength, durability, and lightness in weight. Then

35 too, I provide a convertible ladder wherein both of the companion sections are equipped with steps rather than rungs to avoid tiresome strain and pressure on the feet of the user, and in addition, I mount these steps in

40 unique hangers or brackets and associate with each step a reinforcing and stress distributing bolt.

Other features and advantages will become more readily apparent from the following description and drawings.

In the drawings:

Figure 1 is an elevational view showing the extension form of ladder employed in orchard work and used by a single occupant.

50 Figure 2 is the side view of the step ladder

formation susceptible of being employed by two workers.

Figure 3 is an elevational view of the improved hinge and latch.

Figure 4 is a top edge view thereof.

Figure 5 is an inside face elevation of the hinge.

Figure 6 is a detail view in section and elevation.

Figures 7, 8 and 9 are elevational views of the novel step hanger bracket.

In Figures 1 and 2, it will be observed that the body of the ladder is composed of a pair of companion sections. For sake of distinction, the primary section is designated generally by the numeral 10 and the secondary companion section by the numeral 11. The first named section comprises a pair of spaced parallel side rails 12 between which are the vertically spaced steps 13. This section is joined to the secondary section 11 through the medium of unique hinges generally represented by numeral 14.

The section 11 embodies complementary side rails 15 disposed in converging relationship and fastened together to afford a pointed end as at 16. The steps on this section are designated by the numerals 13 as in the first instance, as all steps are the same.

Particularly do I wish to emphasize the provision of the balancing and steady base 17. This is seen in Figure 1 and comprises extension legs 18 whose upper ends are bevelled off as at 19 and securely fastened to the intermediate portion of the rails 12. This disposes the legs in outwardly and downwardly diverging relationship. The lowermost step 20 has its extended ends 21 fastened to the intermediate portion of the extension legs. Then too, I provide reinforcing vertically arranged bolts 22 fastened to the step 20 and the lower end portions of the rails 12.

Each hinge 14 is the same in construction, and a description of one will suffice for both. Attention is therefore invited to Figures 3, 4, and 5, wherein it will be observed that each hinge embodies elongated plate-like leaves 23 and 24 having overlapped ears 25 and 26 at their inner ends. These ears are pivoted

together through the medium of a pin 27, and they are provided with registrable keeper holes 28 and 29 for reception of the retaining pin 30 carried by the spring latch strip 31.

5 This provides a novel stress distributing hinge joint permitting the sections to be swung into longitudinal alinement or into the diverging relationship seen in Figure 2 and permits the retaining pins 30 of the latch 31 10 to be seated in either of the keepers 28 or 29 as the case may be. The abutting feature of the ears relieves the pivot pin of undue strain.

15 The feature of particular importance is the provision of the spring-pressed latch serving to hold the hinge leaves in either of their adjusted positions and to insure rigidity whether the latter be formed as seen in Figure 1 or transformed into a step ladder as seen in Figure 2.

20 I next invite attention to Figure 6, wherein the detail of the step construction is shown. Each step is fastened to the rail through the medium of a novel hanger bracket generally 25 designated at 32. The bracket comprises a plate 33 having upper and lower retaining flanges 34 and end flanges 35. A tongue 36 is struck out from the plates and leaves a semi-ovate opening as at 37. The tongue 30 functions as a key and is adapted for reception in the keyway or groove 38 formed in the ladder rail.

25 In addition I provide a retaining and bracing bolt 39 for each step which passes through the rails and is fastened in place as seen in Figure 6. This construction provides a simplified arrangement for dependable connection of the steps with the rail.

30 With this arrangement it is obvious that 40 the sectional construction of the ladder is appropriate for orchard use in that it avoids damage to the limbs and the fruit, and is expeditious in use. A ladder of this kind is dependable, sturdy, comfortable, and otherwise susceptible of fulfilling the requirements of a device of this class.

35 The convertible feature permits the ladder to be used as an extension ladder as seen in Figure 1, or as a step ladder as seen in Figure 50 2, at which time the upper section 11 is disposed downwardly with the point 16 firmly resting on the ground. The base structure 17 prevents side slipping and firm anchorage in the pointed end also cooperates therewith 55 in insuring efficient maintenance of the step-ladder.

40 It is thought however, that persons skilled in the art to which the invention relates will be able to obtain a clear understanding of the 60 same after considering the description in connection with the drawings. Therefore a more lengthy description is regarded as unnecessary.

45 Minor changes in shape, size, materials and 65 arrangements of details coming within the

field of invention claimed may be resorted to in actual practice if desired.

I claim:

A ladder of the character described comprising, in combination, a pair of side rails having pairs of transverse, elongated notches in their opposed sides, said notches having arcuate inner walls, step boards extending between the rails, and means for mounting the step boards on the rails, said means comprising flat metallic plates disposed in abutting engagement with the ends of the step boards and interposed between said step boards and the rails, said plates having in-turned flanges on their marginal edges extending over the end portions of the step boards in a manner to embrace said step boards therebetween, and elongated tongues struck outwardly from intermediate portions of the plates for disposition in the notches, said tongues having arcuate free edges conforming substantially to the curvature of the inner walls of the notches.

70 In testimony whereof I affix my signature.

CHARLES E. WHITE.
